Primary Examiner — Patricia Palasik*(74) Attorney, Agent, or Firm* — Keri Ann K. S. Krzykowski(57) **CLAIM**

The ornamental design for an oil filter changing sleeve, as shown and described.

DESCRIPTION

FIG. 1 is a perspective view of a first presently preferred embodiment of the oil filter changing sleeve of my new design;

FIG. 2 is an elevational view thereof from the front, the elevational views from the right, left, and rear thereof being identical;

FIG. 3 is a top plan view thereof;

FIG. 4 is a bottom plan view thereof;

FIG. 5 is a second perspective thereof from a higher elevation to show the depth of the opening in my design;

FIG. 6 is a perspective view of a second presently preferred embodiment of the oil filter changing sleeve of my new design;

FIG. 7 is an elevational view thereof from the front, the elevational views from the right, left, and rear thereof being identical;

FIG. 8 is a top plan view thereof;

FIG. 9 is a bottom plan view thereof;

FIG. 10 is a second perspective thereof from a higher elevation to show the depth of the opening in my design;

FIG. 11 is a perspective view of a third presently preferred embodiment of the oil filter changing sleeve of my new design;

FIG. 12 is an elevational view thereof from the front, the elevational views from the right, left, and rear thereof being identical;

FIG. 13 is a top plan view thereof;

FIG. 14 is a bottom plan view thereof; and,

FIG. 15 is a second perspective thereof from a higher elevation to show the depth of the opening in my design.
